VEHICLE JACK

William H. Cook, Collier City, Fla.

Application December 19, 1934, Serial No. 758,194

2 Claims. (Cl. 254—94)

This invention relates to vehicle jacks and the main object is to provide a jack operated by the momentum or movement of the vehicle to raise any wheel of the same clear of the ground or 5 road.

Another object is to provide a device of this kind wherein novel and effective means is provided for preventing retrogressive or accidental lowering or falling back of the vehicle after it is 10 once raised.

Another object is to provide a jack of this kind in simple, practical and convenient form including an arcuate shoe or rocker having arms supporting a saddle or seat for placing beneath the 15 vehicle axle, the said seat being eccentric to the arc of the rocker so that as the vehicle moves forwardly the rocker will elevate the axle, a foot being slidably mounted through the trailing end of the rocker and having automatic means where- 20 by said foot will maintain contact with the ground and will lock in this position to prevent retrogressive or rearward movement of the rocker and vehicle. To prevent lateral displacement or falling of the jack provision is made to attach a 25 strap which may encircle the adjacent wheel of the vehicle.

With these and other objects in view the invention resides in the novel construction and arrangement of parts as hereinafter fully set forth 30 and claimed.

In the drawing:

Figure 1 is a side view of the jack under a vehicle axle and wheel showing the position preliminary to elevating the wheel.

Figure 2 is a similar view showing the wheel raised.

Figure 3 is a rear end view of the jack alone.

Referring now with more particularity to the drawing the jack comprises an arcuate elongated 40 shoe or rocker 4 serrated along its convex lower face 5 and provided near one end with an arm 6 extended from its concave inner face 7 and joined at some distance from the rocker by another and angularly disposed brace arm 8. At the 45 end the arm 6 has an arcuate laterally widened saddle or seat 9. The rocker is seen in the drawing to be eccentric to the seat 9, that is, the frontal end 10 (as referring to the direction of movement in lifting as will be pointed out) of the rocker is a greater distance from the seat than the rear end 11. The arrangement thus is such that by placing the jack under the vehicle the seat 9 may bear under the axle A thereof with the rear end 11 contacting the ground B beneath, 50 while the front end 10 of the rocker extends for-

wardly and upwardly (Figure 1). Then by moving the vehicle forwardly in the direction of this front rocker end 10 the rocker will roll over the ground until it rests on the axle A and the attached wheel C will be elevated from the ground. 5

In order to prevent the vehicle from rolling backward and down off the jack a foot or foot bar 12 is provided and same is slidably mounted adjacent the inner end of a cleft 13 cut out in the rear end 11 of the rocker 4 between the sides 10 thereof, the said foot having a medial longitudinal slot 14 in which plays a pin 15 passed through the sides of the rocker. When the rear end of the rocker rests on the ground this foot 12 will, of course, be forced up in the cleft 13 to clear, but 15 as the jack rocks forward to lift the vehicle the foot will fall of its own weight down through the cleft and its lower serrated end 16 will maintain contact with the ground as shown in Figure 2. The rear edge of the foot 12 is provided with 20 ratchet teeth 17 and a dog 18 is fulcrumed at 19 in the cleft 13 rearwardly of the foot with its pointed end or nose 20 engaging said teeth 17 and its rear handle end 21 protruding from the rocker. The weight of the handle 21 is such that it over- 25 balances the dog and tends to move the nose end 20 up but the distance between the fulcrum 19 and the toothed edge of the foot holds this nose end pointed angularly downward and in engagement with the teeth 17. Thus as the 30 foot 12 moves downward the nose 20 plays over the teeth 17 and by engagement therewith prevents the foot from again sliding upward. The foot then contacts the ground and prevents the jack from rolling back and allowing the 35 vehicle to fall as will be readily evident. To lower the handle 21 may be raised to disengage the dog from the foot 12 which then moves up and allows the rocker 4 to roll back. To prevent the jack from falling or slipping sideways a strap 40 22 is passed through an eye 23 secured to the arm 6 and around the rim or tire D of the adjacent wheel C and buckled as at 24 thus holding the jack upright. Also this strap prevents the jack from simply sliding forward as the vehicle moves 45 and if such should occur will "start" or pull on the jack as the wheel continues to turn.

While I have herein set forth a certain preferred embodiment of my invention, it is understood that I may vary from the same in minor 50 structural details, so as best to construct a practical device for the purpose intended, not departing from the spirit of the invention and within the scope of the appended claims.

I claim:

50

55

1. In a jack, an arcuate rocker, an axle seat eccentrically supported within the rocker, and an adjustable foot slidably mounted at the end of the rocker nearest the axle seat, the said foot having ratchet teeth, and a gravity operated dog on the rocker engaging the said teeth to releasably lock the foot in a depressed position.
- 5

2. In a jack, an axle seat, arms extended from the seat, an arcuate rocker supported by the arms

eccentrically disposed relative to the seat, the end of the rocker nearest the seat having a cleft, a foot slidably mounted through the cleft and adapted for movement out through the cleft away from the axle seat, ratchet teeth formed on the foot, and a gravity operated dog normally engaging the said teeth to hold the foot in extended position.
